METHOD OF MAKING GOLD LEAF AND
PRODUCT THEREOF

Frederick Demel, Grantwood, N. J.

Application June 15, 1936, Serial No. 35,351

9 Claims. (Cl. 29—18)

The invention relates to the production of improved gold leaf of any desired facial dimension and thickness and the product thereof.

Generally, this invention relates to the production of gold, its alloys and other metals, usually a so-termed precious metal, of any desired dimension of thickness, inclusive of thickness of the magnitude of beaten gold.

My process comprises generally the subjection to rolling operation of a plate of gold in facial engagement with a plate of base metal, until the plate of gold is reduced in thickness to the desired dimension, and then suitably removing the base metal and deriving the gold in desired status.

15 Pursuant to preferred forms of my process, gold or equivalent metal as a composite with other metals, usually a relatively base metal, say, a three-layer composite, i. e., one layer of base metal on the opposing sides of such gold layer, is subjected to continuous rolling treatment, whereby the thickness of such gold layer is reduced to the desired dimension, thereafter removing the layer of base metal fully from one face of such rolled composite, while removing the 20 layer of base metal from the opposite face but partially, then employing such partially removed metal as a support in a subsequent continuous treatment effecting the freeing of the gold, and then positioning the free gold continuous upon a 25 strip of paper or equivalent, or otherwise as desired.

30 Illustrating the instance of gold and gold alloys, pursuant to my preferred procedure, the initial composite may be formed of a plate of gold of a thickness which is readily handled, the plate desirably having a uniform thickness throughout its length, applying a layer of base metal, say copper, having a thickness appreciably greater than that of the gold plate, to one face of the gold plate, and applying to the opposite face of the gold plate a separate layer of copper or other base metal, the effective thickness of one layer of base metal being less than the effective thickness of base metal on the opposite face. Such 35 three-layer composite is then subjected to successive stages of rolling, thereby substantially proportionately reducing the respective thicknesses of the three layers, the rolling or equivalent operation being carried out until the thickness of the intermediate gold layer is reduced to the desired dimension. Thereupon, the rolled composite is subjected on both faces to a bath of a medium unaffected the gold layer but capable of removing, usually dissolving, the base 40 metal, such as dilute nitric acid for copper as

the base metal, the duration of such treatment being carried out to wholly remove the base metal from one face of the gold, say, the layer of base metal of lesser thickness. The resulting two-layer composite is then subjected to a subsequent bath of removing medium unaffected the gold layer but capable of removing the base metal layer, say a solution of nitric acid for copper, the base metal layer being disposed below the gold layer, thus freeing the gold. The freed 45 gold is suitably treated as desired. Usually, the freed gold is positioned upon a length of paper for mechanical support and to facilitate its use in the arts.

Gold derived by my process by virtue of the 50 rolling treatment, is characterized by a physical structure of high density, uniformity of thickness, uniformity of reflected and translucent color and luster, and other superior physical characteristics, notably full deviance of tendency to 55 curl. In contrast with the gold leaf made pursuant to my process, beaten gold, by reason of its manner of manufacture, is inherently devoid of uniformity of thickness, i. e. "thinness", being thicker at and toward its edge portions, and in consequence does not possess uniformity of color by reflected light nor uniformity of color by translucent light. Also, in contrast with my gold leaf pursuant to my process as set forth herein, electrolytic gold by reason of the presence of 60 release of hydrogen gas at the cathode upon which the gold is deposited, has the tendency to curl, particularly at its edges, which curling tendency persists upon subdividing the electrolytic gold leaf. Also, electrolytic gold by reason 65 of its production by electrodeposition, is constituted of non-densified crystals and other physical constitution giving rise, particularly when alloyed with base metals such as silver and/or copper, to non-uniformity of color by reflected 70 light and non-uniformity of color by translucent light.

By my process the resultant gold is obtained of indefinite length, whereas beaten gold is limited in superficial dimension by the inherent restrictions imposed by the beating operation.

If desired, gold produced by my process may have a thinness comparable to that of beaten gold, that is to say, of the order of four millionths of an inch.

The "base" metal on one face of the gold plate of such composite, which is subjected to rolling treatment, may be different from the "base" metal on the opposite face of the gold plate, and the thickness of the respective layers of "base" 80

metals may be equal or unequal, the objective being that upon subjecting the rolled composite to a suitable removing medium, the "base" metal layer or layers are removed, and the freed gold disposed to enable the same to be suitably supported and utilized as desired.

Further features and objects of the invention will be more fully understood from the following detail description and the accompanying drawing, in which

Fig. 1 is a side elevation, largely diagrammatic indicating an initial treatment of rolling of a three-layer composite, the intermediate layer being, say, of gold or its alloy, and the two layers respectively on opposite sides of the gold layer being of base metal.

Fig. 2 is a side elevation, similar to Fig. 1, also in diagrammatic form, illustrating a subsequent stage of rolling treatment.

Fig. 3 is an elevation in vertical section, in diagrammatic form, illustrating a continuous treatment, pursuant to my invention, viz., the subjecting of such rolled three-layer composite strip to successive baths, firstly, for the removal of base metal wholly from one face of the gold layer and the partial removal of base metal from the opposite face of the gold layer, by means of a medium unaffected the gold layer but capable of removing, usually dissolving, the base metal, thence to a subsequent bath for the whole removal of such partially removed layer of base metal, thence through suitable washing and/or other treating baths for the removal of all foreign material, and ultimately positioning the freed gold upon one face of a roll of indefinite length of a paper strip.

Fig. 4 is a detail vertical section on line 4—4 of Fig. 3.

Fig. 5 is a perspective view of gold or equivalent freely lying on a strip of paper, of indefinite length, and wound as a roll.

Throughout the specification and claims, for simplicity, I employ the term "leaf" to designate variant dimensions of thickness or thinness applicable to a plate, foil, film, etc., inclusive of leaf; also, I employ the term "gold" to designate pure gold, gold alloys and other metals, usually a precious metal, the "leaf" of which is desired to be produced; also, by the term "copper" I designate a metal other than "gold", usually a base metal, employed on either or both faces of the intermediate "gold" layer, utilized in carrying out my process.

Referring to the drawing which illustrates preferred individual steps and preferred sequence of individual steps for carrying out my process:

In Fig. 1, I illustrate a three-layer composite strip comprising an intermediate layer 10 of "gold", on one face of which is applied a layer 11 of "copper"; a layer 12 of "copper" is applied to the opposite face of the "gold" layer. The thickness of one layer, say, the layer 12, is illustrated less than the thickness of the opposite layer, i. e. the layer 11.

At 13, 14, are indicated a pair of rolls of a conventional or other approved rolling mill, the number of additional sets of rolls 13, 14, being as desired.

As is indicated in Fig. 1, the normal operation of such chain of rolls 13, 14, functions primarily to reduce the over-all thickness of the composite metal layers, without substantial increase in width of the composite metal layers.

In Fig. 2, illustrating a subsequent stage of the rolling operation indicated in Fig. 1, the over-all thicknesses of the rolled composite three layers

are indicated relatively and exaggerated for the sake of clearness.

Fundamentally, by such rolling or equivalent operation, the thickness of the intermediate "gold" layer 10 is gradually reduced to uniform thickness by the successive rolling treatments, until the desired thickness or thinness of the "gold" layer 10 is that of the "leaf" to be obtained. By such rolling or equivalent operation, the opposing layers 11, 12, are substantially proportionately reduced in individual thickness dimensions.

Desirably, the rolling or equivalent operation is carried out to obtain a composite sufficiently pliable to afford winding into a coil.

The resulting length of composite metal layer is then suitably treated for the full removal of the "copper" layer 12 and the partial removal of the "copper" layer 11.

If desired, as indicated in Fig. 3, the thus coiled multiple layer composite, as is indicated at 15, may be continuously fed as an indefinite length into a bath 16, of suitable medium for removing "copper", say, a bath of dilute nitric acid for the removal of copper, such bath being contained in a suitable tank 17. At 18, 19, I indicate suitable supply and withdrawal piping, preferably for maintaining a desired strength of solution. By such removing treatment the layer 12 of "copper" is wholly removed and the layer 11 of "copper" is partially removed. Most preferably, the piping 18, 19, forms a part of a circuit connecting with a suitable supply of nitric acid or equivalent "copper" removing medium, and also with suitable means serving for the recovery of "copper", if desired.

Advantageously, the procedure of removal of the opposing "copper" layers is carried out in a continuous manner, as is indicated in Fig. 3, the bath 20 representing a bath, say of dilute nitric acid, for the completion of the removal of the theretofore partially removed layer 11 of "copper". 15a indicates such two-layer composite, the "gold" layer 10 lying above the partially removed, under layer 11 of "copper", resulting from the treatment in the previous removal bath 16. The bath 21 represents a bath such as of water, and the bath 22 represents a bath such as alcohol, such bath 21 of water being illustrative as a suitable medium for the removal of nitric acid, or equivalent, and the bath 22 of alcohol being illustrative as a suitable medium for the removal of water or other equivalent.

In the treatment in the bath 20, the two-layer composite 15a, comprising a lowerly disposed "copper" layer and an upwardly disposed "gold" layer, is preferably passed in transit upon the surface of the bath 20, the thus freed "gold leaf", indicated at 10a in Fig. 3, being suitably mechanically supported and conveyed through the respective baths 20, 21, 22, etc. for final disposition.

Fig. 3 illustrates also a method of final disposition of the "gold leaf" 10a by laying the "gold" in free status upon a strip of suitable material such as of paper, supplied, say, from a roll 23 and conveyed in suitable adjacent relationship relative to the freed "gold leaf" 10a, as by the inter-mediation of a roller 24 about which the paper strip 23a is passed to elevate the freed "gold" 10a from the bath 22 and freely lay the "gold" upon the paper strip.

Fig. 5 illustrates such "leaf" of "gold" 10a, of great length and of uniform thickness throughout its length, freely positioned upon an indefinite

length of paper strip 23a resulting from the above or equivalent treatment. Roll gold, i. e. gold leaf wound (spirally) on paper and/or other inert carrier, finds wide application in the industrial 5 art of stamping requiring continuous, i. e. repeated operations, as in stamping book covers, tipping of sweat bands and inside linings of hats, brand and trade-name marking of various products, as is well known to those skilled in the art.

10 The tank 21 is preferably provided with supply and withdrawal piping, indicated at 26, 27. The tank 22, which may contain an alcohol bath, is provided with supply and withdrawal piping 26', 27', connected preferably in circuit with a source of alcohol, and more preferably arranged for recovery of alcohol content.

15 At 28, 28a, are indicated mechanical transferring means for elevating and transferring the released indefinite length of "gold" film 10a from bath to bath, as from bath 20 to the succeeding bath 21, and correspondingly from the bath 21 to the succeeding bath 22. Such transferring means advantageously comprises, as shown, an endless belt indicated at 29, suitably driven and controlled as pointed out more particularly hereinafter.

20 Preferably, the "gold" film 10a in its transit through the respective baths and its transfer from bath to bath, and from final bath to ultimate disposition, as positioning upon a paper strip 23a, is actuated and controlled in synchronism with one another at the respective stages. Advantageously, such synchronous transit and transfer is had by positive drive of and by positive interconnection of the respective actuated parts, including a suitable main shaft 30, and most preferably including a set of feed rolls 31, 31, for positively feeding the composite strip 15a to the first bath, say, the bath 20 of the "copper" removing medium, a desirable arrangement being indicated in Fig. 3. The positive drive from the shaft 30 to the respective film transferring means 28, 28a, etc., and including the paper-gold film positioning roll 24, are indicated in the form of screws secured 25 to the shaft 30 and meshing with suitable screw gears 32, respectively secured to the shafts of the stated actuated devices, such as indicated with respect to the rollers 33 driving the respective belts 29 of the transfer devices 28, 28a, etc.

30 In illustration of the employment of different base metals for the layers 11, 12, zinc may be employed on one face and copper on the other face, the thickness of such opposing layers of zinc and copper being coordinated with respect to the rates of solution of zinc and copper, in the removing medium, so as to provide for the whole removal of one base metal from one face of the rolled gold layer, the layer on the opposing face being either but partially removed, or otherwise 35 of suitably reduced thickness, to serve as a support in the subsequent treatment for the release of the gold film.

35 Whereas, I have set forth my invention in respect to specific details of the more preferred procedure, it is understood that many changes and modifications may be made without departing from the spirit of the invention.

40 In the below appearing claims, the terms "gold", "copper" and "leaf" are employed as above defined. Further, I employ the term "great length" to define a length materially exceeding the length of beaten gold, usually not greater than seven inches.

45 I claim:

50 1. The method of continuously producing gold

5 in leaf form, which comprises subjecting a strip of gold of an indefinite length continuously intermediate opposing strips of copper of indefinite lengths to continuous thickness reducing operation under pressure, to attain the desired thickness of the leaf, then wholly removing the copper from one face of the gold, and removing the copper from the opposing face of the gold while recovering the gold in leaf form.

55 2. The method of continuously producing gold 10 in leaf form, which comprises subjecting to continuous pressure treatment a composite layer of individual layers of gold and copper of indefinite lengths, the layer of gold being disposed intermediate layers of copper, one layer of copper 15 being of less effective thickness than the opposing copper layer, then wholly removing the copper from one face of the gold layer, and removing the copper from the opposing face of the gold layer while recovering the gold in leaf form. 20

3. The method of continuously producing gold leaf which comprises subjecting to continuous mechanical rolling a composite layer of individual layers of gold and copper of indefinite lengths, the layer of gold being disposed intermediate layers of copper, the thickness of one copper layer being less than that of the other copper layer, then removing wholly the copper from one face of the gold layer by immersion in a bath of suitable solvent, and continuously removing the copper 30 from the opposing face of the gold layer while continuously recovering the gold in leaf form. 25

4. The method of continuously producing gold 35 leaf which comprises subjecting to continuous mechanical rolling, a composite layer of individual layers of gold and copper of indefinite lengths, the layer of gold being disposed intermediate layers of copper, one layer of copper being of less effective thickness than the other copper layer, 40 then continuously wholly removing the copper metal from one face of the gold layer by immersion in a bath of suitable solvent while partially removing the opposite copper layer, then continuously removing the theretofore partially 45 removed copper from such opposite face of the gold layer by immersion in a bath of suitable solvent, and continuously recovering the gold in leaf form.

5. The method of continuously producing gold 50 leaf which comprises subjecting to continuous mechanical rolling, a composite layer of individual layers of gold and copper of indefinite lengths, the layer of gold being disposed intermediate layers of copper, one layer of copper 55 being of less effective thickness than the other copper layer, then continuously wholly removing the copper layer from one face of the gold layer by immersion in a bath of suitable solvent while partially removing the opposite copper layer, 60 then continuously removing the theretofore partially removed copper from such opposite face of the gold layer by immersion in a bath of suitable solvent, the gold layer being disposed above the copper layer while passing through the second mentioned bath, and continuously recovering the gold in leaf form. 65

6. The method of continuously producing gold leaf which comprises subjecting to continuous mechanical rolling, a composite layer of individual layers of gold and copper of indefinite lengths, the layer of gold being disposed intermediate layers of copper, one layer of copper being of less effective thickness than the other copper layer, 70 then continuously wholly removing the 75

5 copper layer from one face of the gold layer by immersion in a bath of suitable solvent while partially removing the opposite copper layer, then continuously removing the theretofore partially removed copper from such opposite face of the gold layer by immersion in a bath of suitable solvent, the gold layer being disposed at the surface level of the second mentioned bath above the copper layer in course of removal of the copper 10 per layer, and continuously recovering the gold in leaf form.

15 7. Gold leaf of great length and having a uniform thickness throughout its length, the thickness of the same being of the order of magnitude of four millionths of an inch and possessing density materially greater than that of electrolytically deposited gold, and characterized by having been worked and possessing uniformity of reflected color and uniformity of translucent 20 color.

20 8. Gold leaf of a great length and having a

5 uniform thickness throughout its length, the thickness of the same being of the order of magnitude of four millionths of an inch, possessing density materially greater than that of electrolytically deposited gold, characterized by having been worked and possessing uniformity of color by reflected light, uniformity of color by translucent light, and devoid of the tendency to curl.

10 9. The method of continuously producing gold in leaf form, which comprises subjecting to continuous pressure treatment a composite layer comprising a layer of gold disposed intermediate layers of materials having mutually different rates of solubility, all of said layers being in continuous strip form of great length, then removing wholly the material from one face of the gold layer by immersion in a bath of suitable solvent, then removing the material from the opposing face of the gold layer while recovering the gold in leaf form.

20 FREDERICK DEMEL.
